UNITED STATES PATENT OFFICE.

EDWIN L. RELLER, OF PORTLAND, OREGON, ASSIGNOR TO THE DUCO ADDING MACHINE COMPANY, OF ST. LOUIS, MISSOURI, A CORPORATION OF MISSOURI.

ITEM-CIPHER-PRINTING MEANS FOR CALCULATING-MACHINES.

1,098,170.

Specification of Letters Patent.

Patented May 26, 1914.

Original application filed October 16, 1911, Serial No. 654,982. Divided and this application filed January 26, 1914. Serial No. 814,322.

To all whom it may concern:

Be it known that I, EDWIN L. RELLER, a citizen of the United States, formerly residing at the city of St. Louis, State of Missouri, but now residing at the city of Portland, in the county of Multnomah and State of Oregon, have invented certain new and useful Improvements in Item-Cipher-Printing Means for Calculating-Machines, (the present application being one divided out of that filed by me October 16, 1911, Serial No. 654,982,) of which the following is a specification.

This application is a division and continuation of one filed by me October 16, 1911, Serial No. 654,982.

The present invention relates to improvements in calculating machines and is more especially applicable to calculating machines of the type embodied in the pending application of Edwin L. Reed, Edwin L. Reller, William L. Swift, and Albert J. Meier, filed April 3, 1911, Serial No. 618,655, the present improvement being directed particularly to the item cipher-printing mechanism for machines of the type therein disclosed.

The object of the present invention is to provide, in a calculating machine, item printing mechanism whereby all ciphers to the right of a selected numeral in a column are brought automatically into printing position, without requiring operation, either manual or otherwise, of the sectors or finger pieces.

In the accompanying drawings forming part of this specification, in which like numbers of reference denote like parts wherever they occur, Figure 1 is a detailed view of a portion of one of the item printing sectors and the associated parts, which control and actuate the item cipher-printing means and, also, control and actuate the accumulator; and Fig. 2 is a sectional view, on an enlarged scale, on the line 2-2, Fig. 1.

The present embodiment of this invention is, as previously stated, applicable particularly to calculating machines of the type disclosed in the above-mentioned application, Serial No. 618,655, and hence reference is here made to that application for a disclosure of the construction and mode of operation of the machine in general and such parts or elements of the machine as control or actuate the item printing means and, also,

the accumulator and its associated mechanism. 55

The mechanism for printing the items and transmitting the same to the accumulator to be totalized is shown in the drawings, and includes the several printing sectors 60 or finger pieces which are mounted to turn independently and concentrically on a shaft 1, each sector or finger piece having a disk-like hub 2 formed on a portion of its circumference with a toothed sector 3 and on 65 another portion of its circumference with the item-printing type 4 bearing consecutively arranged numerals, any one of which may be brought to the printing point by appropriate rotation of the sector. The 70 toothed-sector 3 cooperates with a longitudinally reciprocatory rack bar 5, there being one of these rack bars for each sector.

The printing portion of each sector or finger piece is provided, according to the 75 present invention, with means whereby the setting of one sector to bring a selected numeral thereon to printing position will automatically set the printing portions of all sectors to the right thereof, in condition to 80 print ciphers, without requiring operation of such sectors, either manually or otherwise to accomplish this result. To this end, the disk-like hub of each sector is provided with a shiftable bar 6, which is slidably 85 guided by grooves 7 in the sector-hub, and the outer end of this bar bears a zero type face 8, which is normally below or within the arc of the type faces 4 and is yieldably retained in such position by the retracting 90 spring 9, which acts on the bar 6, but this zero type face is capable of being brought into arcuate alignment with the other type characters by a shifting movement of the bar 6, whereby the zero type face is brought 95 into printing position.

The reciprocatory bar 5 is formed with a longitudinally-extending slot 10, and the forward end of this slot has an enlargement 11, an inclined or cam surface 12 being 100 between the narrower portion of the slot and its enlargement. A plate 13 is mounted at the left-hand side of each rack bar, the front end of each plate being slotted and guided by a cross-rod 14, and each plate is 105 normally held in forward position by a tension spring 15. Each plate 13 has an upwardly and rearwardly sloping incline 16,

upon which the adjacent lower end of the bar 6 bears under the influence of its spring 9, and each plate is, also, formed with a slot 17, which forms a shoulder 18. A set 5 of independently movable arms 19, of a number corresponding to the number of rack bars and plates, are pivotally mounted on a cross-bar 20, the latter having its ends fitted in longitudinal slots 21 in the side 10 plates 22 to permit the cross-bar 20 and the arms 19 thereon to shift bodily in a forward and rearward direction, such parts, however, being returned to and held in normal position by the tension springs 23 attached to 15 depending lugs on the arms. The free end of each arm 19 is provided with a laterally-turned and downwardly-inclined finger 24, which extends through the slot enlargement 11 of the rack bar and the slot 17 of the 20 plate 13, the finger of each arm engaging beneath or underlying the finger of the next adjacent arm to the right, as shown clearly in Fig. 2. By this arrangement, rotation of a sector to bring a selected numeral to 25 printing position will cause its coöperating rack bar 5 to move toward the right, Fig. 1, and during such movement the cam or inclined surface 12 will operate upon the respective finger 24 to elevate it, and lifting 30 of one of these fingers 24 causes lifting of the remaining fingers to the right, the remaining fingers being thereby presented to the respective shoulders 18, and forward movement of the cross-bar 20 will cause the 35 raised fingers to abut against the shoulders 18 and thereby shift the corresponding plates 13 forwardly or toward the right in Fig. 1. the inclined surface 16 of each plate operating upon the respective bar 6 bearing 40 thereon and causing the latter to shift in a manner to bring its zero type face 8 into printing position. Operation of the cross-bar 20 is effected in the usual manner by the main operating element (not shown) of the 45 calculating machine, to which it is suitably connected. No ciphers will be printed to the left of the set sector, as the finger 24 of each arm 19 is capable of setting fingers to the right thereof, the zero type faces on 50 the sectors to the left, therefore, remaining depressed below the printing line.

The forward end of each plate 13 is guided relatively to its respective rack bar by a pin 25 on the plate which operates 55 freely in a longitudinal slot 26 in the rack bar, it being, of course, understood that the forward ends of the rack bars 5 and the coöperating plates 13 are supported in the usual manner in the entrance of the accumulator (not shown) and the upper forward 60 edge, each rack bar being provided with a rack 27 to coöperate with its respective printing wheel of the accumulator.

The operation of the mechanism is as follows; The entering of the items is accom-

plished in the same manner as described in the afore-aid application, Serial No. 618,655, that is to say, by depressing and rotating the finger pieces or sectors, and when each finger piece or sector is depressed or rotated, the rack bar 5, which is operatively connected thereto, moves forwardly into the accumulator. The forward movement of a rack bar 5 by manipulation of its respective sector causes the inclined or cam surface 12 70 on the rack bar to ride beneath the corresponding finger 24, thereby raising such finger, and the finger so raised will act simultaneously to raise all fingers to the right thereof, and each of the raised fingers 75 will be then positioned opposite to the corresponding shoulder 18 on the respective plates 13, and, hence, when the cross-bar 20 is moved forwardly, or toward the right, Fig. 1, all the raised fingers will abut against 80 the corresponding shoulders 18, with the result that the respective plates 13 are, also, moved forwardly, causing the inclined surfaces 16 thereon to operate upon and force upwardly the bars 6 bearing the zero type 85 faces 8, the zero type faces being thereby brought to printing position.

I claim:

1. In a calculating machine, the combination, with a plurality of printing devices 90 each embodying an endwise movable bar bearing a cipher printing type face, and means acting upon said bar for normally holding its upper type face in non-printing position, of means operative when one of 100 said devices is actuated to move the bars of all devices to the right thereof in one direction, for setting the cipher type faces of those bars in printing position.

2. In a calculating machine, the combination, with a plurality of printing devices each provided with a groove, a bar slidable therein and bearing a cipher printing type face, and means for normally holding the bar inwardly of the groove, of means operative 105 when one of said devices is actuated to move the bars of all devices to the right thereof outwardly of their respective grooves, for setting the cipher type faces of those bars in 110 printing position.

3. In a calculating machine, the combination of a printing device provided with an endwise movable bar bearing a cipher printing type face, a reciprocatory element associated with said device and provided with a 120 cam, means acting upon said bar to normally hold the same in engagement with said cam and with its cipher type face in non-printing position, and means for reciprocating said element to move said bar in one direction for setting the cipher type face thereof in printing position.

4. In a calculating machine, the combination of a printing device provided with a groove, a bar slidable longitudinally in said 125

groove and bearing a cipher printing type face on its outer end, a reciprocatory element associated with said device and provided with a cam, means acting upon said 5 bar for normally holding the same inwardly of said groove with its cipher type face in non-printing position and its inner end engaged with said cam, and means for reciprocating said element to move said bar outwardly of said groove and set its cipher type 10 face in printing position.

5. In a calculating machine, the combination of a printing sector carrying a relatively adjustable cipher printing device, 15 means for normally holding said device in non-printing position, an endwise movable plate provided with an incline coöperative with said cipher printing device, and means for shifting said plate in one direction to set 20 the cipher printing device in printing position.

6. In a calculating machine, the combination of a printing sector carrying a longitudinally movable bar bearing a cipher printing type face at its outer end, an endwise movable plate having an incline, means acting upon said bar for normally holding the inner end thereof against said incline and said cipher printing type face in non-printing 30 position, and means for moving said plate in one direction to bring said cipher printing type face into printing position.

7. In a calculating machine, the combination of a printing sector carrying a relatively movable cipher printing device, a reciprocatory element provided with an incline coöperative with said cipher printing device, and means for operating said element to shift said cipher printing device 40 bodily endwise in one direction into printing position.

8. In a calculating machine, the combination of a printing sector carrying a relatively movable cipher printing device, a reciprocatory element provided with a shoul- 45

der and an incline, the latter being coöperative with the cipher printing device, an arm movable into engagement with said shoulder, and means for reciprocating said arm when so engaged to operate said element and shift said cipher printing device into printing 50 position.

9. In a calculating machine, the combination of a set of printing sectors, each having a relatively adjustable cipher printing 55 device, a rack bar operative by each sector, a set of members one coöperative with each rack bar, and adapted to set said cipher printing devices, a set of arms each bearing a finger, said fingers being arranged in overlapping relation, means on each rack bar for setting its respective finger in operative position thereby to cause all fingers to the right thereof to be set correspondingly, and means for shifting said fingers to operate 60 said members, the actuated members setting the corresponding cipher printing devices in printing position.

10. In a calculating machine, the combination of a set of printing sectors, each carrying a relatively adjustable cipher printing device, a bar operative by each sector and having a slot formed with an incline, a plate coöperative with each bar and having an incline coöperative with the respective cipher 75 printing device, an arm for each bar having a finger lying in the slot thereof, each finger underlying the next adjacent finger to the right thereof, the incline of each bar adapted to set its respective finger when such bar 80 is shifted, and means for operating the set fingers to shift said plates and thereby set the corresponding cipher printing devices in printing position.

In testimony whereof I hereunto affix my 85 signature in the presence of two witnesses.

EDWIN L. RELLER.
